(74) Attorney, Agent, or Firm — Bruce Stone LLP; Joseph Bruce

(57) **CLAIM**

The ornamental design for a ceiling fan motor housing and light kit, as shown and described.

DESCRIPTION

FIG. 1 is a perspective view of the present design; FIG. 2 is a front view of the present design; FIG. 3 is a rear view of the present design; FIG. 4 is a left side view of the present design; FIG. 5 is a right side view of the present design; FIG. 6 is a top view of the present design; FIG. 7 is a bottom view of the present design; and, FIG. 8 is another perspective view of the present design. The broken lines in all FIG. views illustrate structural portions of the ceiling fan motor housing and light kit that form no part of the claimed design.

1 Claim, 8 Drawing Sheets(56)
